UNITED STATES PATENT OFFICE.

ADOLF W. KEUFFEL, OF MONTCLAIR, NEW JERSEY, ASSIGNOR TO KEUFFEL & ESSER COMPANY, OF HOBOKEN, NEW JERSEY, A CORPORATION OF NEW JERSEY.

PROCESS OF MAKING DRAWING INSTRUMENTS.

Application filed April 24, 1922. Serial No. 556,192.

To all whom it may concern:

Be it known that I, ADOLF W. KEUFFEL, a citizen of the United States, residing at 763 Bloomfield Avenue, in the township of 5 Montclair, in the county of Essex and State of New Jersey, have invented certain new and useful Improvements in the Process of Making Drawing Instruments, of which the following is a specification.

10 This invention relates to the process of making drawing instrument legs, and the novelty consists in the steps of the process, as will be more fully hereinafter pointed out.

15 Under former methods of manufacture it was necessary to take solid blanks of metal large enough to include the hinge or shoulder portions of the separate legs, and by milling and a long tedious process cutting away the metal so as to form the legs with shoulder or hinge portion attachments 20 as required.

25 My method has eliminated the necessity of milling and makes use of a blank of substantially the cylindrical form required, which is quickly and easily tapered to the exact form required by means of the use of a screw machine, thereby effecting a new cylindrical shape for the legs which is most

30 desirable, and accomplishing this with very slight labor and very material saving in manufacturing cost. The shoulder or hinge portion is then formed separately and brazed to the leg, and a clamping means for 35 a needle or a pencil point is also separately brazed to the leg, thereby eliminating the necessity of using a metal blank of large proportions and cutting it down so as to include said shoulder and clamping means. In my 40 process I first harden the needle as required for final use and then drive it into the drive-fit boring in the lower end of the leg, thereby eliminating any necessity for hardening after the needle has been driven into said 45 leg.

50 Referring to the drawings Figure 1 is a top plan view of a cylindrical blank adapted for use in my process; Figure 2 is an end view of Figure 1; Figure 3 is a top plan view of an upper leg which has been formed from the blank of Fig. 1; Figure 4 is an end view of the same looking in from the right-hand end; Figure 5 is a top plan view of the shoulder or hinge member; Figure 6 is the 55 same as Figure 3, but with the shoulder of

Figure 5 brazed thereto; Figure 7 is an end view of Figure 6 looking in from the right-hand end; Figure 8 is an end view of Fig. 9 looking in from the left-hand end; Figure 9 is a side elevation of a lower leg of the 60 drawing instrument; Figure 10 is an end view of Fig. 9 looking in from the right-hand end; Figure 11 is an end elevation of the clamping blank; Figure 12 is a side elevation of the clamping blank shown in Fig. 65 11; Figure 13 is the same as Fig. 9, but with the clamping blank brazed thereto and bored; Figure 14 is a top plan view of Fig. 13 in which the lower end of the leg has been sawed; Figure 15 is another form of 70 drawing instrument leg having a boring at the lower end to receive a needle point, and with the upper portion of the leg broken away for convenience in illustration; Figure 16 is a top plan view of the needle point 75 adapted to be mounted in the leg shown in Fig. 15; Figure 17 is the same as Figure 15, but with the needle point of Fig. 16 mounted therein; and Figure 18 is a top plan view of the lower end of an upper leg 80 having a mouth adapted to receive the tongue of the lower leg, the upper portion being broken away for convenience in illustration.

85 In carrying out my process a cylindrical blank 20 of nickel silver, or of any metal of a similar degree of density and hardness, is cut to the desired length, as shown in Fig. 1. The blank 20 is then tapered by means of a screw machine to the exact size required, 90 as shown in Fig. 3. The taper turning device made by and adapted to be attached to the Brown & Sharpe Mfg. Co. automatic lathe embodies such a well known screw machine. In this machine the taper turning 95 device, in which a lathe tool is mounted, is attached in one of the six holes of the turret and the tool comes into position at a certain specified time controlled by means of the cams of the machine at each cycle. As the 100 turret is driven along the axis of the machine the lathe tool in the taper turning device turns whatever shape is desired on the raw material in the revolving chuck of the machine. This is one of the many different well known screw machines on the market. A curved shoulder 21 is then cut therein, 105 and a circular groove 22 is cut therein to facilitate in the handling of the instrument and the small end is tapered at 23, thereby 110

forming the leg 24. For certain of my drawing instruments I then cut a mouth 29 in the base of the leg 24 with a deeper slot 30 in the base of said mouth 29, thereby forming two spring gripping members 31. A shoulder or hinge member 25, circular in form and having a bevelled edge 26 and a flat portion 27 adapted to fit a curved shoulder 21 of the leg 24, is made separately. 10 The shoulder or hinge member 25 is then brazed to the shoulder 21 of the leg 24, so that the flattened portion 27 lies in the curved shoulder portion 21.

A lower leg is shown in Figures 8 to 14, 15 inclusive, in which a leg 28 has a cylindrical shoulder 32 and a tongue 33, both of which are made integral therewith. A metal blank 34 having an arc 35 at its base is adapted to be brazed near the lower end of the leg 28, 20 the arc 35 being adapted to fit the leg 28, and the blank 34 is then bored at 36, and the lower end of the leg 28 is then sawed so as to form an opening therein at 37, which cut passes through the blank 34 as is shown 25 in Fig. 14. Where it is desired to mount the needle directly in the leg I harden a needle 38 to the degree desired for actual use and drill a hole 40 in a leg 39 so that the hole 40 is a snug fit for the needle 38, and I 30 then drive the needle 38 in the hole 40 in the usual well-known manner.

In carrying out my process a long cylindrical blank may also be used, and this may be tapered as described, and the length required for a leg is then cut and the remaining blank portion again tapered and cut until the blank is used up. 35

I claim:

1. The process of making a drawing instrument upper leg consisting of cutting a cylindrical metal blank to the length of upper leg desired, tapering the same to size required by means of a screw machine, cutting out a curved shoulder at the larger end, 40 brazing a separately made shoulder member to said curved shoulder and cutting a groove in the lower end of the said leg adapted to receive a tongue of a lower leg. 45

2. The process of making a drawing instrument leg consisting of cutting a cylindrical metal blank to the length of the leg desired, tapering the same to size required by 50 means of a screw machine, cutting out a

curved shoulder at the larger end, brazing a separately made shoulder member to said 55 curved shoulder, and drilling a hole in the lower end of said leg, and driving into same a previously hardened needle.

3. The process of making a drawing instrument upper leg consisting of cutting a 60 cylindrical metal blank to the length of upper leg desired, tapering the same to size required by means of a screw machine, cutting a circular groove at about the middle of said leg, cutting out a curved shoulder in the larger end of said leg, brazing a separately 65 made shoulder member to said curved shoulder and cutting a groove in the lower end of the said leg adapted to receive a tongue of a lower leg. 70

4. The process of making a drawing instrument leg consisting of cutting a cylindrical metal blank to the length of leg desired, tapering the same to size required by 75 means of a screw machine, cutting a circular groove at about the middle of said groove, cutting out a curved shoulder at the larger end, brazing a separately made shoulder member to said curved shoulder, and drilling a hole in the lower end of said leg and driving into same a previously hardened needle. 80

5. The process of making a drawing instrument lower leg consisting of cutting a cylindrical metal blank to the length of lower leg desired, tapering the same to the 85 size required by means of a screw machine, cutting a cylindrical shoulder and tongue at the larger end of same, brazing a metal blank having a base adapted to fit said leg to the lower end of said leg, boring a hole 90 through said blank transversely to the longitudinal axis of said leg, and sawing said blank and lower end of leg on the longitudinal axis of said leg.

6. The process of making a drawing instrument leg consisting of tapering a portion of a long cylindrical metal blank to the length of leg desired by means of a screw machine, cutting the same to the length desired, cutting a shoulder at the larger end of 95 said leg and securing a separately made shoulder member to said leg shoulder. 100

In testimony whereof I affix my signature.

ADOLF W. KEUFFEL.
